(57) **CLAIM**

The ornamental design for a hand tool for fence clip wire, as shown and described.

DESCRIPTION

FIG. 1 is a first perspective view of a hand tool for fence clip wire showing my new design;

FIG. 2 is a second perspective view thereof, in a second orientation; and

FIG. 3 is a third perspective view thereof, in a third orientation and on an enlarged scale; wherein

FIG. 4 is a left side elevational view of FIG. 3, the right side being a mirror opposite image;

FIG. 5 is a rear elevational view of FIG. 4;

FIG. 6 is a front elevational view of FIG. 4;

FIG. 7 is a top plan view of FIG. 6;

FIG. 8 is a bottom plan view of FIG. 6; and,

FIG. 9 is an enlarged-scale section view taken along line IX-IX in FIG. 1.

The broken lines in the drawing represent environmental subject matter that forms no part of the claimed design. The dashed cross-section lines in FIG. 9 form no part of the claimed design.
